UNITED STATES PATENT OFFICE.

ROLAND A. BEATTY, OF NEW YORK, N. Y.

MAGAZINE-HAMMER.

1,331,228.

Specification of Letters Patent.

Patented Feb. 17, 1920.

Application filed May 18, 1918. Serial No. 235,285.

To all whom it may concern:

Be it known that I, ROLAND A. BEATTY, a citizen of the United States, residing at Bronx, in the county of Bronx and State of New York, have invented certain new and useful Improvements in Magazine-Hammers, of which the following is a specification.

This invention relates to nail-driving implements, and more especially to those which are provided with a magazine; and the object of the same is to produce an implement of this kind in which a number of nails or tacks of a variety of sizes are fed to the point of use and delivered thereby so as to be placed by the user and then sunk in place.

A further object is to provide means whereby nails or tacks of a variety of sizes may be selectively fed or supplied to the point of use.

Another object is to provide means whereby the magazine can be charged from time to time.

Yet other objects will appear in the following specification and claims, and reference is made to the drawings herewith and in which:—

Figure 1 is a side elevation and

Fig. 2 a central longitudinal section of this hammer complete,

Figs. 3 and 4 are enlarged cross sections on the lines 3—3 and 4—4 of Fig. 2,

Fig. 5 is an enlarged sectional detail showing the gate mechanism, taken on the line 5—5 of Fig. 2, and

Fig. 6 is an enlarged perspective detail showing the nail-holding mechanism.

The handle 1 of this hammer is a hollow cylinder, preferably of metal and preferably cast integral with the right-angular head 2 thereof, the same having a driving face 3 at its lower end and a nail-drawing claw 4 at its upper end as usual. Within the handle near the head is fastened a transverse partition 5 in whose center is rotatably mounted a trunnion 6 and one end of a shaft 7 constituting the axis of a magazine, the balance of the same consisting of a group of tubes 8 externally of the same size but having bores of different size as best seen in Fig. 3, so that in effect the magazine contains a plurality of chambers constituting small magazines for nails, brads, or tacks having heads of different sizes. The trunnion 9 at the rear end of the shaft 7 may be rotatably mounted in a socket at the center of a cap 10 which

screws on the rear end of the handle as shown at 11 and which, when unscrewed and removed, gives access to the open rear ends of the small tubes so that any one which may be empty may be recharged. From said trunnion 9 projects a pin 12 adapted to be set into any one of a series of notches 13 with which the rear end of the handle is provided, so as to hold the magazine in any position to which it has been adjusted, for a purpose yet to appear. Through the partition 5 at one side of the trunnion 6 is an opening, and within this opening is mounted the inlet end of a main or feed tube 15 which leads thence forward, makes a bend downward as seen in Fig. 2, and extends along the outer side of the hollow head 2, opening through the lower end of the same at a point just forward of the driving face 3. The notches 13 are so disposed in the rear end of the handle that, according as the point 12 is set in them, one or the other of the tubes 8 are brought into registry with the inlet end of the feed tube 15; and accordingly the operator may select which magazine tube he is to align with the feed tube, and therefore which size or shape of nails, etc. is to be supplied. Meanwhile all the other tubes have their front ends closed by the partition 5, while their rear ends are of course closed by the cap 10 as long as the latter remains in position. I do not wish to be limited, however, to tubes 8 having different size bores as shown in Fig. 3. If we should assume, for instance, that this device is to be employed by a lather who is to drive a large number of nails which are all of one size and shape, it might be of advantage for him to have a magazine with a plurality of tubes 8 which are all alike and the bore thereof capable of receiving the head of lathing tacks or nails as will be clear. When now he has exhausted the charge within one tube, he has but to remove the cap and turn the point 12 to another notch 13 so as to bring another tube into registry with the main tube, and then to continue the operation as before.

Feed mechanism must be provided within this main or feed tube so as to deliver nails or tacks one by one to the point of use, and this mechanism is best shown in Figs. 2 and 5. Said feed tube is interrupted at the point 20, and within this interruption stands an upright ring constituting a bridge 21. Slidably mounted over this bridge are two gates 22 and 23, the former having a hole in its

body through which the latter projects as best seen in Fig. 2. These gates stand substantially at right angles to each other and in planes which cross each other as shown 5 in Fig. 5, and their upper ends are respectively pivoted at 24 and 25 on pins connected with a rod 26 which is mounted for reciprocation through the partition 5 and has a knob or handle 27 at its rear end. The 10 latter is turned out through a slot 28 in the side of the main handle, and a spring 29 bears it normally forward. In this position the gate 23 stands raised and the gate 22 closed as seen in Fig. 5. When now the 15 handle is inclined with the head 2 downward a little, a nail or tack passes out of the tube 15 under the gate 23, through the bridge 21, and against the gate 22; and when the operator puts his finger over the knob 27 20 and retracts the rod 26 so that the gates assume the opposite position from that illustrated in Fig. 5, the nail in question may pass under the gate 22 which now restrains it, and continue along the tube to the point 25 of use. When the operator removes his finger from the knob 27, the spring 29 restores the parts to the position shown in Fig. 5, and another nail or tack is released, ready to be supplied at the next impulse. 30 The pin 25 on which the gate 23 is pivoted is really the downturned end of the rod 26, and it is continued downward as at 35 into a fork 30 which projects through a slot 31 in the feed tube just above its outlet 35 end through the hole in the driving face 3. Close above the fork stands a plate 32 projecting through another slot 33 in said tube, this plate being carried at the lower end of another rod 36 which rises throughout the 40 hollow head 2, makes a right angular bend as shown in Fig. 2, and is carried to the rear through the partition 5 and preferably along the lower side of the handle. At its rear end it is turned outward as at 36 and 45 carries a knob 37 beyond a slot 38 in the handle, a spring 39 bearing this turned out end normally forward the same as with the uppermost knob and spring already described. It is seen that the two rods 50 described reciprocate within the handle and are entirely independent of the rotary movement of the magazine, and also that they do not interfere with its withdrawal and reinsertion as described above. 55 The operation of this device is as follows:—Assuming that the magazine has been set so that a certain size of tacks is fed. Each tack passes under the gate mechanism already described and in the manner set forth above, and travels over the bend in the feed tube 15 until its point rests upon the plate 32 as shown in Fig. 2. When the lower knob 37 is retracted the plate is drawn out from under the tack, so that the latter 60 drops with its point through the fork 30

and its head resting thereon; and now the knob 37 is released so that the spring 39 moves the plate 32 over the head of the tack and it stands as seen at the extreme bottom of Fig. 2 with its point projecting beyond 70 the driving face 3. The point of the tack may now be seated in the wood by a gentle blow, in a manner well understood by carpenters and those familiar with tools of this character. Immediately after having seated 75 this tack or nail, the operator retracts the other knob 27, with the result that the fork 30 is withdrawn from beneath the head of this tack and it is released. This he can do almost automatically with his thumb at the 80 top when he makes the stroke which seats the tack, and therefore as he withdraws or retracts the hammer for a blow on its driving face 3, he leaves the tack sticking in the wood, and the next action is to sink it by a 85 proper driving action as usual. Meanwhile it is quite possible that he may become sufficiently expert to cause the movement of the hammer by a swinging action to project another tack from the tube 8 through 90 the gate mechanism shown in Fig. 5, which mechanism is naturally and automatically actuated as he retracts the upper knob 27 in withdrawing the plate. In this way a large number of tacks or nails can be rapidly driven, one blow seating the tack and the next sinking it as will be understood. 95

The foregoing description and the drawings have reference to what may be considered the preferred, or approved form of 100 my invention. It is to be understood that I may make such changes in construction and arrangement and combination of parts, materials, dimensions, et cetera, as may prove expedient and fall within the scope of 105 the appended claims.

Having thus fully described my invention, what I claim as new and desire to secure by Letters Patent, is:—

1. In a magazine hammer of the type described, the combination with the magazine proper contained within the handle, a feed tube leading thence forward and downward through the head of the hammer to the point of use, and means at said point for holding 110 a tack while it is seated; of a pair of gates projecting across said feed tube, and manually operable mechanism for withdrawing one gate and projecting the other, for the purpose set forth.

2. In a magazine hammer of the type described, the combination with the magazine proper contained within the handle, a feed tube leading thence forward and downward through the head of the hammer to the point 115 of use, and means at said point for holding a tack while it is seated; of a pair of gates projecting across said feed tube, and a rod slidably mounted in the handle and to which said gates are respectively pivoted, said 120

handle being longitudinally slotted and the rear end of the rod turned outward through the slot, a knob thereon, and a spring bearing this end normally forward, for the purpose set forth.

3. In a magazine hammer of the type described, the combination with the magazine proper contained within the handle, a feed tube leading thence forward and downward through the head of the tool to the point of use, and means at said point for holding a tack while it is seated, said feed tube being cut away between the magazine and said point of use; of a bridge standing within the cut-away portion of the feed tube, a pair of gates whereof one passes through an opening in the other and both overlie the bridge, and a manually reciprocated rod to which said gates are pivoted, for the purpose set forth.

4. In a gate mechanism for the purpose set forth herein, the combination with a feed tube cut away at an intermediate point, a hollow bridge standing within the cut-away portion, a pair of gates whereof one has a hole through which the other passes so that their bodies lie practically in planes at right angles to each other, the gates overlying said bridge, and a manually operable rod having pins to which the outer ends of said gates are pivoted; of means for feeding elements into one end of said tube and handling them at the other end thereof.

5. In a gate mechanism for the purpose set forth herein, the combination with a feed tube cut away at an intermediate point between its ends, a hollow bridge standing within the cut-away portion, a pair of gates whereof one has a hole through which the other passes so that their bodies lie practically in planes at right angles to each other, the gates overlying said bridge, and a manually operable rod having pins to which the outer ends of said gates are pivoted; of a magazine having a plurality of longitudinal cells, means for bringing the cells selectively into alinement with one end of said feed tube, and means for grasping the articles delivered by the other end of the feed tube, as described.

6. In a magazine hammer of the type set forth, the combination with a tubular handle having a driving head at one end, a partition across the handle, a feed tube opening through said partition and leading thence to the driving face of said head, and a cap for movably closing the open end of said handle; of a magazine consisting of a group of tubes surrounding a shaft, the trunnion at one end of the latter being journaled in said partition and that of the other in said cap, and means for setting the magazine with the selective tube in register with said main tube.

7. In a magazine hammer of the type set forth, the combination with a tubular handle having a driving head at one end, a partition across the handle, a feed tube opening through said partition and leading thence to the driving face of said head, and a cap removably closing the open end of said handle; of a magazine consisting of a group of tubes surrounding a shaft, the trunnion at one end of the latter being journaled in said partition and that of the other in said cap, the rear end of said handle being notched, and a point projecting radially from the rearmost trunnion and engageable with said notches selectively, for the purpose set forth.

8. In a magazine hammer of the type set forth, the combination with a tubular handle having a driving head at one end, a partition across the handle, a feed tube opening through said partition and leading thence to the driving face of said head, and a cap screwed onto said handle and having a central socket; of a magazine consisting of a group of tubes surrounding a shaft, the trunnion at one end of the latter being journaled in said partition and that of the other in said socket in the cap, the rear end of said handle being notched, and a pin in the rear trunnion for engaging said notches selectively, for the purpose set forth.

9. In a magazine hammer, the combination with a tubular handle and a tubular head, a magazine in the former, a feed tube leading from the magazine throughout the length of the head and opening at one point through its driving face, and means for controlling the feed of tacks through said tube; of a fork movable in a slot at the lower end of said feed tube, a plate movable in a slot in said tube just above the fork, and manually operable mechanism for actuating these elements to deliver the tacks one by one.

10. In a magazine hammer, the combination with a tubular handle and a tubular head, a magazine in the former, a feed tube leading from the magazine throughout the length of the head and opening at one point through its driving face, and means for controlling the feed of tacks through said tube; of a fork movable in a slot at the lower end of said feed tube, a plate movable in a slot in said tube just above the fork, rods rising from said fork and plate and bent and extending into said handle, the latter being slotted, and knobs carried by said rods and operable over said slots, for the purpose set forth.

In testimony whereof I affix my signature in presence of two witnesses.
